John Rogers.

Pls. 159,6

John Rogers, of New York, N.Y.
Letters Patent No. 159,6, dated May 27, 1862.

The schedule referred to in these Letters Patent and making part of the same.

To all whom it may concern,

Be it known that I, John Rogers of the City and State of New York, have invented or produced a new and original design for a group of Statuary and I do hereby declare that the following is a full and exact description of the same.

The group is called the Village School Master.

and consists of three figures A, B and C.

The figure A is sitting on the bench D. his right leg E is crooked over his left F, with his right hand G, he marks the points of his argument on his left hand H, his hair is gathered in a cap I, behind, his spectacles K are resting over his forehead. He is dressed in the old fashioned style of coat and short clothes and is looking towards the figure C. which is also seated on the bench D. The thumb of his right hand I, is thrust into the armhole of his waistcoat M, in his left hand N, he holds a newspaper O, his feet P and Q. both rest on the ground R.

He is dressed in the old fashioned style similar to figure A, and is looking towards him.

The central figure B. stands behind the bench D. He stands with his left foot on the ground and his right on the bench D. His left hand S, rests on the shoulder of figure C. His right elbow T, rests on his leg U, in his right hand V, he holds a pipe W, he is looking towards figure C.

Having thus described my invention what I claim and wish to secure by Letters Patent, is a design for a group of statuary as herein fully described and shown.

Witnesses,

Henry A. Booth.

Jas. R. Brevoort.
